UNITED STATES PATENT OFFICE.

CHARLES HUGH DUFFY, OF NORTH LAUREL, MARYLAND,

SPARK-PLUG.

1,190,130.

Specification of Letters Patent.

Patented July 4, 1916.

Application filed January 6, 1913. Serial No. 740,502

To all whom it may concern:

Be it known that I, CHARLES HUGH DUFFY, a citizen of the United States, residing at North Laurel, in the county of Howard and State of Maryland, have invented certain new and useful Improvements in Spark-Plugs; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to spark plugs for internal combustion engines and has for its object to provide a spark plug so designed, constructed and arranged as to obviate the tendency to short circuit the secondary current employed.

Generally speaking and with reference to spark plugs of ordinary construction it is possible to short circuit the same in three ways. First, by means of a bridge of short circuiting material such as oil laden with carbon, water and the like extending across the spark gap and connecting the two electrodes. Secondly, by means of a coating of carbon deposited on the insulator within the shell of the plug so as to provide an electrical conductor from the central electrode to the metal shell of the plug, and thirdly, by reason of the passage of the secondary current over the surface of the insulator outside of the shell of the plug, the current passing over the insulator from the outer portion of the central electrode to the shell of the plug.

This invention has for its object to prevent the short circuiting of the plug in any of these mentioned manners so as to insure a proper jumping or arcing of the secondary current at the spark gap.

A further object of the invention is to so construct the insulator and the central electrode as to relieve the insulator of any undue stress or strain which would tend to crack or disrupt the insulator.

The co-efficient of expansion of metals varies considerably according to their characters and according to the alloys thereof, and it might be said as a general proposition that there is no metal or alloy of metals suitable for use as spark plug electrodes whose co-

efficient of expansion is the same as that of porcelain which is the usual material of which spark plug insulators are constructed. The consequence of this is that when the plug is subjected to the heat generated in an internal combustion engine the expansion and contraction of the central metal electrode differs from the expansion and contraction of its surrounding insulator, thus placing upon the insulator undue stresses and strains which frequently result in cracking or disrupting the insulator, thus rendering the plug useless to further hold the high tension current employed.

This invention consists in the novel construction and arrangement of the electrodes of the plug and in so forming the same that a strong capillary attraction is exerted at the spark gap of the plug to break a short circuiting bridge of liquid at the spark gap.

The invention further consists in the construction of the insulator and of the metal shell of the plug so as to allow the lower portion of the insulator to freely expand and contract, and which is so constructed as to place in the path of the secondary current sufficient resistance to prevent the passage of the secondary current over the inclosed portion of the insulator to short circuit the current.

The invention further consists in so constructing the lower inclosed portion of the insulator that one or more clean annular rings will be maintained around the lower portion of the insulator between the central electrode and the metal shell of the plug thereby providing a break in any deposit of short circuiting material so as to prevent the passage of the secondary current over the lower inclosed portion of the insulator.

The invention further consists in the construction of the insulator and the central electrode which places in the path of the secondary current sufficient resistance so as to prevent the passage of current over the outer exposed portion of the insulator to short circuit the current between the outer portion of the electrode and the metal shell of the plug.

The invention further consists in certain other novel details of construction and in combinations of parts, all of which will be first fully described and afterward specifically pointed out in the appended claims.

Referring to the accompanying drawing: Figure 1 is a vertical sectional view of a spark plug constructed in accordance with this invention. Fig. 2 is a bottom end view 5 of the lower portion of the plug illustrating the two electrodes. Fig. 3 is a fragmentary view illustrating the lower threaded portion of the plug and illustrating the position of the electrodes. Fig. 4 is a similar 10 view illustrating a modification of the electrodes, and Fig. 5 is a similar view illustrating a still further modification of the electrodes.

Like numerals of reference indicate the 15 same parts throughout the several figures in which:

1 indicates the spark plug and 2 the metal shell, said shell 2 comprising the lower body portion 3 and the upper gland 4, the said 20 two parts being threaded together at 5 in the manner as illustrated in Fig. 1.

The lower body portion 3 of the shell is provided with a relatively large bore 6 which communicates with the lower relatively small bore 7, an inclined shoulder 8 25 being formed between the two bores 6 and 7 in the manner as illustrated in Fig. 1, the extreme lower portion of the shell surrounding the bore 7 being threaded at 9 for 30 threaded connection with the combustion chamber of an internal combustion engine.

10 indicates the lower electrode of the plug which is preferably secured to the lower threaded end 9 of the plug in any 35 convenient manner, the body portion 3 of the shell being provided above the enlarged chamber 6 with a shoulder 11 to receive the insulating core in the manner as shown in Fig. 1, while the gland 4 of the shell is provided with an inwardly extending annular portion 12 to engage the insulating core in the manner as shown in the drawing, the said gland 4 being provided with an opening 13 sufficiently large to permit of the 45 said gland passing freely over the outer portion of the insulating core.

14 indicates the insulating core of the plug which may be constructed of any suitable heat resisting insulating material, the 50 said insulating core 14 being shaped in the manner as illustrated in Fig. 1, the extreme upper portion being preferably swelled as illustrated at 15 the said insulating core being provided at substantially the center 55 thereof with an enlargement 16 providing suitable shoulders 17 and 18 for engagement with the body portion and gland of the shell.

19 indicates the lower inclosed portion of 60 the insulating core, said lower inclosed portion being provided with a plurality of annular chambers 20, said annular chambers being deep and relatively narrow, while a plurality of annular webs or flanges 21 are formed on the lower inclosed portion of the

insulating core by reason of the annular 65 chambers 20, the same being arranged in the manner as shown in Fig. 1. About midway of the insulating core is provided a small central longitudinal bore 22, while the lower inclosed portion of the insulating 70 core is provided with a relatively large central bore 23, the upper exposed portion of the insulating core being also provided with a relatively large central bore 24, said relatively large bores 23 and 24 communicating 75 with the small central bore 22, thereby forming a shoulder above and below the said small central bore 22 in the manner as shown in the drawing.

25 indicates the upper threaded portion 80 of the central electrode 26, said central electrode 26 being provided with a swell 27 or with a small threaded nut, said swell or threaded nut 27 being of a size to snugly fit the relatively large bore 23 in the lower 85 inclosed portion of the insulating core and to engage the shoulder below the small central bore 22 in the manner as shown in Fig. 1, a suitable gasket or other packing means being employed to prevent leakage through 90 the insulating core in the usual manner.

28 indicates the upper portion of the central electrode which, as shown in the drawing, is provided with a lower enlarged portion 29, said lower enlarged portion being of 95 a size to snugly fit the relatively large bore 24 in the upper portion of the insulating core, the said enlarged portion 29 being internally threaded to receive the threaded end 25 of the lower electrode 26, that part 100 of the upper portion 28 of the electrode being reduced as shown at 30 in order to prevent contact with the wall of the relatively large bore 24 in the manner as shown in Fig. 1. An annular flange 31 is formed 105 above the reduced portion 30 and is of such a size as to cover the end of the relatively large opening 24 but which is not in contact with the upper end of the insulating core, an annular groove 32 being provided 110 above the annular flange 31 to receive a wire terminal; the extreme upper end of the portion 28 being headed at 33 to provide a finish for this portion, the secondary wire terminal being held between the head 33 115 and the annular flange 31 in the manner which will be perfectly apparent from an inspection of the accompanying drawing.

The extreme lower end of the central electrode 26 is provided with a long and relatively narrow longitudinal slot 34, the lower electrode 10 approaching the central electrode 26 at the slotted end thereof so as to provide a spark gap 35 between the said two electrodes, it being essential to the proper 120 operation of this plug that the lower electrode 10 face the slot 34 in the central electrode, the relative position of the elec- 125

trodes being further illustrated in Figs. 2 and 3.

Referring now to Fig. 4 which illustrates a modification of the construction just described it will be seen that the lower electrode 10 is provided with a long and relatively narrow slot 34, the central electrode 26 approaching the slotted electrode 10 to provide a suitable spark gap between the two electrodes.

In Fig. 5 the lower electrode 10 is curved in the manner as illustrated, the curved end of the electrode being provided with a long and relatively narrow slot 34 extending below the spark gap, the end of which approaches the central electrode 26 to provide a suitable spark gap between the ends of the two electrodes.

Having thus fully described the several parts of this invention its operation is as follows: By reason of the law of capillary attraction liquids are attracted into capillary openings or interstices, the extent of attraction being in proportion to the size of the capillary opening or interstice. By forming either the lower end of the central electrode or the lower end of the lower electrode with a long and relatively narrow capillary slot or cut a capillary attraction is provided for any liquid coming in contact with the end or sides of the said capillary slot or cut; consequently when the fellow electrode is properly positioned with respect to the said slot or cut any liquid bridging the spark gap will be drawn into the capillary slot or cut by capillary attraction in such manner that any bridge existing will be broken by reason of the attraction of the liquid into the capillary slot or cut.

As will appear from the accompanying drawing the slot or cut which may be formed in either one of the electrodes is arranged longitudinally of the electrode and is open from end to end, although it is not essential to a proper operation of this device that the cut or slot extend entirely through the electrode as the capillary action will take place even though the slot or cut be partially closed or even though the slot or cut simply extends partially through the electrode and not entirely across the same, it being of course understood that the exact shape or form of the cut or slot is immaterial as far as any capillary action is concerned, it simply being essential that the slot or cut be of a capillary size so as to attract liquid thereto by reason of the position of the capillary slot excess liquid will be drained therefrom by gravity.

Referring now to the construction of the body portion of the central electrode it will be seen that only the relatively short threaded portion 25 of the central electrode is clamped within the insulating core; con-

sequently the expansion and contraction of this relatively short piece of metal is quite negligible as it allows the entire inclosed lower portion of the insulator to freely expand and contract while the upper portion of the insulator is equally free to expand or contract unhampered by the central electrode, and it is obvious that likewise both the lower and the upper portion of the metal electrode is free to expand and contract without clamping or placing upon the insulator any undue stress or strain which would tend to injure the same. The central threaded portion of the central electrode is preferably cemented within the insulator to insure a gas tight construction and to prevent accidental rotation of the electrode within the insulator.

Referring now to the insulator it will be seen that the lower inclosed portion thereof which is provided with deep, narrow annular chambers 20, is of a size which provides an annular space or chamber surrounding the lower inclosed portion of the insulator and between said portion and the inner wall of the metal shell of the plug; while it will also be seen that the said lower inclosed portion of the insulator is of a circumference considerably in excess of the lower bore or chamber 7 of the plug. By reason of this construction when in operation the extreme lower end of the insulator extends beyond the sides of the lower bore or chamber 7 and upon compression of the engine piston any carbon or short circuiting material is thrust against the said extreme lower end of the insulator to which surfaces it adheres, thus guarding the upper portion of the said inclosed end of the insulator.

When the plug is placed on an internal combustion engine the lower bore or chamber 7, the upper space or chamber 6, surrounding the inclosed portion of the insulator and the said deep and narrow annular chambers in the insulator are filled with air at atmospheric pressure. When therefore compression occurs in the engine cylinder the air within the lower bore or chamber 7 is compressed upwardly into the annular chamber 6 surrounding the insulating core and is compressed within the deep annular chambers 20 formed in the insulating core. This compression existing within the annular chambers 20 formed in the insulating core is obviously forced to the bottom of the said annular chambers 20 and consequently any foul gas which enters the said plug is prevented from entering the extreme bottom of the said annular chambers 20 to deposit as carbon or other short circuiting material but deposits upon the extreme bottom surface of the insulator and upon the peripheries of the said annular webs or flanges 21; consequently in course of time these surfaces

will become foul with a coating of short circuiting material but the extreme bottoms of the said deep annular chambers 20 are maintained in a relatively clean and 5 uncoated condition. It therefore matters not how foul or coated the said surfaces of the insulator become so long as there is a single clean ring maintained around the lower portion of the insulator, for the reason that the current in 10 order to short circuit over the surface of the insulator must have a continuous path and any break or series of breaks will effectually prevent the passage of the current 15 over the inclosed portion of the insulator, and so long as the extreme bottoms of the said annular chambers 20 are maintained in a clean condition the coated portions of the insulator do not provide a conductor for the 20 passage of the current over the same. This obviously would not exist to the same extent if the lower inclosed portion of the insulator extended down into the lower bore or chamber 7 as the deep, annular chambers 25 20 in the insulator would then be subjected to the foul gas of the combustion chamber and would more readily accumulate a coating of short circuiting material which would doubtless extend to the bottoms of the said 30 annular chambers 20. The arrangement of the annular chamber 6 surrounding the lower insulating core and the relatively small lower bore or chamber 7 prevents the foul gases from the combustion chamber 35 from entering the bottoms of the annular chambers 20 in the insulating core, while the fact that the extreme lower surface of the insulating core extends beyond the edges of the lower bore or chamber 7 causes the major 40 portion of the foul gases to deposit their short circuiting material upon the extreme lower surface of the insulating core. Plugs constructed in accordance with this invention when subjected to extreme conditions 45 of oil and carbon have shown conclusively that nearly the entire deposit of carbon has occurred on the extreme lower surface of the insulating core, while the extreme bottoms of the annular chamber 7 were maintained 50 in a clean condition even after the constant use of the plug for a period extending over six months. It will be further noted that the relatively large central bore 23 in the insulating core extends inwardly of the core 55 a distance greater than the lower depending inclosed portion of the core, thus allowing the depending portion of the core to be free of all stresses and strains which might otherwise tend to crack or disrupt the insulator by reason of the external chambered construction thereof. It will therefore be 60 understood from an inspection of Fig. 1 that the current to pass over the surface of the lower inclosed portion of the plug must

start at the extreme inner end of the relatively large bore 23, pass downwardly along the walls thereof to the extreme lower end of the insulating core and then pass upwardly over the sides of the inclosed portion of the core following the contour of 65 each of the annular chambers 20. That the current cannot pass in this direction if any one of the bottoms of the said annular chambers 20 is maintained in a clean condition is perfectly apparent from an inspection of 70 the accompanying drawing taken in connection with the above description and explanation.

Referring now to the upper exposed portion of the insulator it will be seen that 80 the upper portion 28 of the electrode passes a considerable distance within the relatively large bore 24, the lower enlarged portion 29 of the said electrode member being in contact with the insulator only at the lower 85 portion of said member. When the two parts of the electrode are threaded together and preferably cemented in position no part of the upper portion of the electrode member 28 is in contact with the said insulator, 90 and consequently current passing into the upper electrode member 28 does not come in contact with the outer exposed portion of the insulator but does come in contact with the lower portion of the wall of the relatively large bore 24. It is therefore a matter of impossibility to effect a leakage of 95 current from the top of the electrode member 28 over the outside surface of the exposed portion of the insulator thereby obviating all possibility of leakage from the top of the insulator to the metal shell of the plug which is always possible and often-times present in spark plugs of usual construction. It will thus be seen from the accompanying drawing taken in connection with this specification that provision has 100 been made to protect the plug against short circuiting in any one of the three previously mentioned ways which are prevalent in 110 spark plugs of usual construction.

Referring again to the slotted or cut electrode arranged to exert a capillary attraction for liquids bridging or tending to bridge the spark gap it may be said that 115 this slotted or cut construction of the electrode presents advantages over a tubular electrode, for the reason that this present construction presents advantages from the standpoint of manufacture over the tubular 120 construction of the electrode and further presents the very material advantage that in the tubular construction of the electrode there is always present the possibility of an infinitesimal quantity of air becoming 125 trapped in the tubular electrode to prevent the capillary action of the same. With the slotted or cut construction of the electrode,

the slot or cut being open its entire length, all possibility of trapping air in the slot or cut is entirely eliminated and thus capillary action of the slot or cut is at all times 5 assured.

It is further essential to a proper operation of this plug that the lower inclosed chambered portion of the insulator be maintained in an enlarged chamber at a point 10 above the relatively small lower chamber of the plug, for the reason that if the said lower inclosed portion of the insulator extended down into the threaded portion of the plug the annular chambers would 15 quickly accumulate a deposit of short circuiting material which would provide a conductor for the current from the central electrode to the metal shell of the plug in order to ground the same.

Having thus fully described the invention what I claim as new and desire to secure by Letters Patent of the United States is:—

1. A spark plug comprising an insulating core, a metal shell and a plurality of electrodes including a central one, said electrodes being separated to provide a spark gap, the said metal shell being provided with an enlarged upper chamber and a smaller lower chamber, the said insulating core being of greater diameter than the said lower chamber and extending into said metal shell providing an annular space between the outer surface of the insulating core and the inner wall of said enlarged upper chamber, the said insulating core being provided within said upper enlarged chamber with a plurality of deep and relatively narrow annular chambers, the lower central portion of said insulating core being provided with a relatively large longitudinal bore surrounding but out of contact with the central electrode of the plug, the outer portion of the insulating core being provided with a relatively large central longitudinal bore surrounding but out of contact with the central electrode in such manner that the central electrode is out of contact with the top and outer surface of the insulating core, one of said electrodes being provided at the spark gap with a capillary slot or cut open at the side of the electrode to exert a capillary attraction for liquid bridging the spark gap.

2. A spark plug comprising an insulating core, a metal shell and a plurality of electrodes, said electrodes being separated to provide a spark gap, the said metal shell being provided with an enlarged upper chamber and a smaller lower chamber, the said insulating core being of greater diameter than the said lower chamber and extending into said metal shell providing an annular space between the outer surface of the insulating core and the inner wall of

said enlarged upper chamber, the said insulating core being provided within said upper enlarged chamber with a plurality of deep and relatively narrow annular chambers, the chambered portion of the insulating core being wholly contained within the 65 said enlarged upper chamber of the metal shell.

3. A spark plug comprising an insulating core, a metal shell and a plurality of electrodes including a central one and terminal connections, said electrodes being separated to form a spark gap, the lower external portion of said insulating core being annularly chambered and internally provided with a deep and relatively large bore 75 surrounding but out of contact with the lower portion of the central electrode, the upper portion of said insulating core being provided with a deep and relatively large bore 80 in such manner that the central electrode 85 and terminal connections are out of contact with the top and outer surface of the insulation.

4. A spark plug comprising an insulating core, a metal shell and a plurality of electrodes including a central one, said electrodes being separated to form a spark gap, the said insulating core being provided with a relatively small central bore, the upper and lower portions of said insulating 90 core being provided with relatively large bores communicating with said relatively small bore, the central electrode comprising an upper and a lower section, the upper section being surrounded by but out of contact with the relatively large upper bore, the lower member of the central electrode being surrounded by but out of contact with the lower portion of the relatively large lower bore in such manner that the upper 95 and lower portions of the insulating core and the upper and lower portions of the central electrode surrounded by said core are free to expand or contract, the lower portion 100 of the insulating core being externally chambered around the enlarged bored portion thereof.

5. A spark plug comprising a plurality of electrodes separated to form a spark gap, one of said electrodes being provided at the 115 spark gap with a capillary slot entering the electrode from the side thereof to attract by capillarity a bridge of liquid across the spark gap.

6. A spark plug comprising a plurality of 120 electrodes separated to form a spark gap, and a capillary opening at the spark gap in one of said electrodes transversely of the electrode to form an elongated aperture in the side of the electrode to prevent the 125 bridging of the spark gap.

7. A spark gap comprising a plurality of electrodes separated to form a spark gap,

one of said electrodes being provided at the spark gap with a capillary slot entering the electrode from the side thereof to attract by capillarity a bridge of liquid across the spark gap, said capillary slot being positioned in relation to the spark gap to drain excess oil from the said slot by gravity.

8. A spark plug comprising a plurality of electrodes separated to form a spark gap, and a capillary opening at the spark gap in and transversely of one electrode to provide an elongated aperture in the side of the

electrode to attract liquid at the spark gap to prevent the bridging of the spark gap, said capillary opening being positioned in relation to the spark gap to drain excess oil from said capillary opening by gravity. 15

In testimony whereof, I affix my signature, in presence of two witnesses.

CHARLES HUGH DUFFY.
